DIE AND DIE HOLDER

Franklin Judge, Greenfield, Mass., assignor to
Greenfield Tap and Die Corporation, a corpora-
tion of Massachusetts

Application July 26, 1939, Serial No. 286,575

2 Claims. (Cl. 10—119)

This invention relates to thread cutting dies and holders therefor and particularly to such dies and holders in which the holder is adapted radially to adjust the die sections accurately to determine the thread dimensions.

The object of the invention is to provide a convenient means for predetermining the setting of the die to desired adjustment.

A further object is to enable the operator to ascertain readily the adjustment necessary for a given depth of thread.

In the accompanying drawing:

Fig. 1 is a sectional elevation of the die and holder;

Fig. 2 is a plan view looking in the direction of arrow 2 in Fig. 1.

Referring to the drawing, Fig. 1 shows a threading device comprising a holder 10, a die 11, a cap 12, and a lock nut 13. The holder 10 is provided with diametrically opposed lugs 15 20 adapted to be received in recesses 16 in the inner face of die 11.

The die 11 is provided with upward extended threading prongs or lands 17, threaded on the inside 18 and having a conical outer surface 19 so that the end of the die is frusto-conical in shape. The cap 12 is provided with an upper annular portion 20 and a lower portion 21. The upper annular portion 20 is provided with a conical recess 22 engaging the conical outer surface 19 of the threading lands 17. The lower annular portion 21 is internally threaded to fit externally threaded portion 23 of the holder 10.

The cap 12 fastened on the holder 10 bears against outer conical surface 22 of lands 17, securing the die 11 in place against holder 10 with lugs 15 positioned in the recesses 16, the conically surfaced ends of the lands 17 projecting through and beyond the forward end of the cap 12. The rotative and axial movement of the cap 11 relative to the holder 10 provides a tightening pressure on the outer surface of lands 17. The prongs or lands 17 flex under the tightening pressure of the cap 12 on the outer surface 22, providing a means for adjusting the thread cut by the die. As the cap 12 is tightened against die 11 the cutting bore 24 of the die is lessened. The diameter of the threaded screw is determined by the bore 24 of the threads 18 as set by the cap 12. When screws are threaded by the die to close tolerances a setting is made of the cap 12 and a sample screw threaded. If this is over or under the measurement sought, the die 11 is corrected by adjusting the setting of the cap 12.

In order to provide for the reading of the initial setting of the cap 12 and the determination of the correct adjustment required to bring the screw size within the tolerances allowed a scale 5 extends around the top side of the upper annular portion 20 of the cap 12. The lines and numbers of the scale 25 are added on the bevel side of the cap and each land 17 is provided with a zero line 26, said zero lines being equally spaced with relation to each other and the number of divisions of the scale 25 is some multiple of the number of the zero lines. Thus the position of the rotating cap can be read against the zero line on any of the lands and the scale 25 may be graduated to any convenient part of the cap rotation corresponding to a fraction of the adjustment of the die. For example, each scale division may represent one-thousandth of an inch of die adjustment and of the corresponding adjustment of the thread depth. The graduations of scale 25 are evenly spaced and the total adjustment plus or minus between successive zero lines is sufficient to take care of any normal readjustment of the die from the trial setting.

25 The graduation of the top of the cap 12 with a number divisible by four, corresponding to the four lands, provides means for reading the setting of the cap 12 on the die 11 and holder 10 from all zero lines 26 by reading the setting at any one of the lands. For instance, as shown here there are thirty-six graduations; if the setting at land A is six, the setting at land B is six plus the nine graduations between each land, or fifteen. The readings at lands C and 30 D, correspondingly, are twenty-four and thirty-three.

The provision of these graduations facilitates the process of readjusting the cap 12 on die 11 after a test screw has been threaded. Before 40 making the trial the original setting of the cap 12 in relation to the zero line on any land 17 is read. This setting will give the readings on the other lands by adding or subtracting the number of graduations between each land. Thus the operator, knowing the correction to be made after the sample threading can adjust the cap 12 on the die 11 against any of the lands 17 whether the setting for that land was originally read or not so that the readjustment may be 45 made readily whatever the position of the holder with relation to the operator.

For instance, if the original setting was six at land A, it was fifteen, twenty-four, and thirty-three at lands B, C and D respectively. If the 50 correction is plus one it can be made from any

one of the zero lines, fifteen to sixteen at land B, twenty-four to twenty-five at land C, thirty-three to thirty-four at land D, six to seven at land A.

I claim:

1. An adjustable die structure comprising a die having a frusto-conical end divided into separate lands relatively radially adjustable, of a holder for the die comprising a body portion and a relatively movable cap housing the die and having a forward end surrounding and contacting the conically surfaced ends of the lands projecting through and beyond said forward end of the cap member whereby slight radial adjustment of said die lands is effected by rotative and axial movement of the cap relative to the holder,

and a die marking at a corresponding point on each of said lands adjacent said cap, said die markings being equally angularly spaced with relation to each other around the axis of the die, and a cooperating 360° circular measuring scale on the end of said cap having the number of its equally spaced divisions a multiple of the number of lands of the die and showing the adjustment of the die sections by the position of said cap divisions relative to each of said die markings.

5 2. An adjustable die structure as set forth in claim 1 in which the separate lands of the die are integrally connected by an annular ring at 10 the base of the prongs.
